MOISTENING MECHANISM FOR
DUPLICATING MACHINES

Hugo Gerlach, Hendon, London, England, assignor to Block & Anderson Limited, London, England, a British company

Application March 20, 1946, Serial No. 655,760
In Great Britain January 28, 1946

10 Claims. (Cl. 91—48)

1

This invention relates to mechanisms for applying liquids to sheets of paper or the like. The problem of applying a liquid uniformly to the surface of a sheet of paper arises in hectographic copying machines in which each copy is taken from a hectographic original or master sheet by bringing into contact with the master a copy sheet previously moistened with a liquid which is a solvent for the hectographic ink used in the preparation of the master. Insufficient damping results in poor copies, whereas excessive damping is detrimental to the master and reduces the total number of copies that can be obtained. The present invention has for its object to provide a liquid-applying mechanism which is capable of satisfying the requirements in hectographic copying machines.

According to the present invention, the mechanism for applying liquid to a sheet comprises a capillary pad arranged in contact with a liquid applying roller adapted to apply the liquid to a sheet passing between it and a further roller, the capillary pad being inclined downwardly away from the area of contact with the liquid applying roller, a pad supporting tray embracing the lower part of the pad, means for supplying liquid to the pad, and a drainage pipe attached to the pad tray at or near the lowermost part of the tray to withdraw any surplus liquid from the tray. Preferably the liquid is supplied to the capillary pad from a reservoir at a lower level by the actuation of a pump, and the drainage pipe discharges into the reservoir.

When used as a damping device for a hectographic copying machine, the applying roller and the co-operating roller of the mechanism according to the invention constitute a pair of feed rollers moistening and advancing the moistened copy sheet to the printing couple, consisting of a master drum and an impression roller. In this arrangement the liquid-applying roller may be driven from the rotation of the master drum to advance the sheet to the bight of the printing couple, the sheet being thereafter fed by the printing couple alone.

To facilitate the understanding of the present invention, a preferred embodiment as applied to a hectographic copying machine will now be described with reference to the accompanying semi-diagrammatic drawings, in which—

Fig. 1 is a side view, partly in section, of the essential components of the machine.

Fig. 2 is an enlarged plan view of the capillary pad and applying rollers, the left-hand portion having the damping roller omitted.

2

Fig. 3 is an enlarged perspective view of a detail.

The printing drum 1 is provided in known manner with means (not shown) for releasably securing on its peripheral surface a master sheet bearing in mirror script in hectographic ink the matter which it is desired to copy. The drum 1 is journaled in bearings in the side frames of the machine, and may be rotated manually by a hand crank or may be motor driven as in known hectographic copying machines. To take a copy, a copy sheet moistened with a solvent for the hectographic ink is fed between the printing drum 1 and the co-operating impression roller 2, which is urged against the printing drum with the appropriate pressure. The mounting and arrangement of the printing drum and co-operating pressure roller form no part of the present invention and consequently are not fully illustrated in the drawing, and will not be further described. In practice, any convenient mounting and arrangement can be adopted.

The present invention is concerned with the damping or liquid-applying mechanism, the preferred embodiment of which as shown in the drawing will now be described.

The surface of the copy sheet which is to come into contact with the master sheet on the printing drum, i.e., the upper surface of the copy sheet in the arrangement according to Fig. 1, is moistened by means of a damping roller 3, which is journaled in the side frames of the machine, the surface of which preferably consists of rubber. The damping liquid is applied to the surface of the roller 3 and thereby transferred to the copy sheet as the latter is fed between the damping roller 3 and a co-operating counter-roller 4, likewise journaled in the side frames of the machine. The shaft of the damping roller 3 carries a gear wheel 5 for driving the damping roller 3 to feed the copy sheet to the bight of the printing couple 1, 2. The gear wheel 5 meshes with a gear wheel 6 journaled in a rocking lever 7 which is mounted to pivot freely about the axis of the damping roller 3 within the limits imposed by stops 9, 10 carried by the adjacent side frame of the machine. A spring 8 extending between the lever 7 and an anchor on the adjacent side frame of the machine, tends to urge the lever 7 towards the stop 10. In this position of the lever 7, the gear wheel 6 is adapted to engage in a toothed segment 11 carried on one end of the printing drum 1. The length of the toothed segment 11 is such that the copy sheet is fed by the damping roller 3, and its counter roller 4 a distance sufficient to ensure

that the leading edge of the copy sheet is gripped between the drum 1 and the pressure roller 2. The segment 11 then runs off the gear wheel 6 and the damping roller 3 is further rotated only by the contact with the copy sheet as the latter is fed by the rotating printing couple 1, 2. With this arrangement, it is possible to moisten substantially right up to the leading edge of the copy sheet, and to cause the moistened copy sheet to be fed to the printing couple 1, 2 in such manner that the leading edge of the copy sheet is in registration with the leading edge of the reproducible area of the master sheet.

The damping liquid is supplied to the damping roller 3 by the capillary action of a felt pad 36 which is supported in a case 37 so as to be inclined upwardly towards the damping roller 3, so that the maximum transfer of liquid to the roller is limited to the capillary feed at saturation and flooding at the roller 3 is avoided. The area of contact between the pad 36 and the roller 3 is as close as possible to the bight of the rollers 3, 4, the direction of rotation of the roller 3 being from the contact area to the bight in the sense of the shortest travel, so that only a very narrow margin at the leading edge of the copy sheet is excluded from the damping operation. To prevent over-damping of the felt pad 36, the lowest point of the upwardly inclined pad case 37 is provided with a drainage hole 44, so that surplus liquid can escape through this hole and the associated overflow pipe 45.

In the preferred construction shown in the drawing, the liquid is supplied to the felt pad 36 from a reservoir 23 at a lower level than the pad 36 by the action of a pump 21, 22 which is actuated automatically during the operation of the machine. For this purpose, the end face of the drum 1 at the opposite end of the toothed segment, carries a projecting pin 12, on which an anti-friction roller is mounted, and which in the rotation of the drum 1 in the printing direction (as indicated by the arrow in Fig. 1) engages and rocks a lever 16. The pin-engaging end of the lever 16 is constituted by a pivoted section 13, which is normally held in contact with a stop 14 on the lever 16 by a spring 15. If, however, for any reason the drum 1 is rotated in the reverse direction, the end section 13 yields before the pin 12 and the spring 15 is temporarily expanded, the lever 16 thus being enabled to retain its rest position. The lever 16 is mounted intermediate its ends on a pivot pin 17 secured to the adjacent side frame of the machine, and the end remote from the drum 1 is connected by a link 18 which is pivotally attached to one arm of a bell-crank lever 19 mounted on a pivot pin 20 carried by the adjacent side frame. The other arm of the bell-crank lever 19 engages the piston rod of the pump piston 21 so as to withdraw the piston 21 against the action of a restoring spring 31. The pump cylinder 22 is immersed in a reservoir 23 which is filled with the liquid 25 through a filler opening provided with a closure cap 24. The pump delivers the liquid through a delivery pipe 26 equipped with a non-return valve 27. In the rotation of the drum 1, the lever 16 is progressively rocked clockwise in Fig. 1 with equivalent displacement of the piston 21 against the action of the spring 31, until the roller 12 releases the lever 16, whereupon the spring 31 causes the pump piston 21 to perform a rapid working stroke, during which the liquid 25 is forced through the delivery pipe 26. To control the length of the working stroke 75

of the pump 21, 22, the return stroke of the arm of the bell crank lever 19 is regulated by a stop lever 29 mounted on a pivot 30. This lever has an arm which projects up through a slot adjacent one of the side frames of the machine. This slot has a series of lateral notches whereby the arm can be arrested in any one of a plurality of pre-determined positions. In Fig. 1, the full-line position of the lever 29 corresponds to the maximum stroke of the pump, and the broken-line position corresponds to the minimum stroke of the pump.

The liquid delivered by the pump 21, 22 through the pipe 26 is discharged on to the felt pad 36. To obtain as uniform a distribution as possible transversely of the machine, the pipe 26 is connected to the inner of two concentric distributing pipes 32, 34. This inner distributing pipe 32 has a relatively small number of large apertures 33 in its upper wall distributed across the width of the machine, the size and/or spacing of the apertures being graded so as to give substantially equal delivery of liquid. The outer distributing pipe 34 has a relatively large number of small apertures 35 in its lower wall, whereby a substantially uniform discharge of liquid to the felt in the transverse direction of the machine is achieved. The end of the inner pipe 32 remote from the delivery pipe 26 and both ends of the annular space between the two pipes 32, 34 are sealed.

The felt pad 36 is carried in a pad case 37 which is slidably in guides 39 secured to the side frames 48, as best shown in Figs. 2 and 3. To ensure free movement in the guides 39 each end of the case 37 carries rollers 38 which engage in the guides. To maintain the free edge of the pad 36 in contact with the applying roller 3, springs 41 are provided which each extend between an abutment 46 on the pad case 37 and a lug 47 on the guide 39. To enable the ready removal of the pad case, each guide is provided in its upper surface with an opening 40 of a size sufficient to permit the free passage of the rollers 38, so that after the pad case 37 has been retracted against the action of the springs 41, the front rollers 38 can be tilted up through the apertures 40, and thereafter the rear rollers can be moved forward and removed through the same apertures. The pad case is inserted in the reverse manner. In the fragmentary view of Fig. 2, the right hand side shows the damping roller 3 in position, whereas on the left hand side the roller 3 is omitted and a plan view of the pad and the counter-roller 4 is shown.

As best seen from Fig. 1, the pad case 37 and the guides 39 are inclined upwardly towards the roller 3, and from the lower end of the base of the case 37 a cover plate 43 extends upwardly and forwardly so as substantially to enclose the concentric distributing pipes 32, 34. At the lowermost part of the pad case 37 and to one end of the felt pad 36, the base of the case 37 is provided with a drainage hole 44 (Fig. 2) from which an overflow pipe 45 (Fig. 1) extends to the reservoir 23. Thus any surplus liquid in excess of the amount which can be taken up by the felt is returned directly to the reservoir, so that flooding with liquid cannot occur. Accommodated within the lower part of the cover plate 43 is an auxiliary felt 42, which serves to enlarge the fluid absorbing capacity and to prevent sudden variations in the amount of fluid transferred to the roller 3 by the felt pad 36.

The sheets to be moistened are fed over a feed

table 49 to the damping mechanism. Adjacent the damping mechanism the feed table has an upwardly inclined feed section directing the leading edge of the sheet to the rollers 3, 4. The cover plate 43 is preferably shaped as shown so as to form a funnel-like entrance leading to the relatively narrow gap between the lower surface of the upwardly inclined pad case 37 and the upper surface of the inclined terminal section of the feed table 49.

On commencing copying operations, it may be necessary to prime the pad 36, and this can be effected either by rotating the drum 1 a suitable number of times, or by a corresponding number of manipulations of the control lever 29 between its extreme positions. During the running of the machine, the lever 29 is set in the position giving the desired supply of damping liquid. If an excessive amount of liquid is supplied to the pad 36 by the pump 21, 22, the surplus liquid is returned to the reservoir 23, and the maximum damping is that corresponding to the amount of liquid transferred to the roller 3 when the pad 36 is saturated, but actual flooding is avoided even when the pump is delivering too much liquid at each stroke.

I claim:

1. In a duplicating machine, means for applying solvent liquid to copy sheets comprising a roller against which said sheets are pressed during their delivery into the machine, a flat capillary pad, a rigid tray supporting said pad, stationary guide means for slidably mounting said tray and the supported capillary pad therein whereby such pad is inclined upwardly towards said roller and is movable in its own plane to present its uppermost longitudinal edge in abutting relationship to the surface of said roller, and means for resiliently urging said tray and the supported pad in the plane thereof towards said roller.

2. In a duplicating machine, means for applying solvent liquid to copy sheets comprising a roller against which said sheets are pressed during their delivery into the machine, a flat capillary pad, a rigid tray supporting said pad, means for slidably mounting said tray and the supported pad in a plane which is coincident with that of the pad and is upwardly inclined towards said roller, spring means for resiliently urging said tray bodily towards said roller whereby the uppermost longitudinal free edge of said pad is continuously pressed on to the peripheral surface of said roller, liquid distributor means overlying and spaced above the lower region of the uppermost side surface of said pad in said tray, a container for solvent liquid, and adjustable pumping means actuated during operation of the machine for delivering a regulable quantity of solvent liquid from said container to said liquid distributor means for discharge by gravity on to the lower region of said pad.

3. In a duplicating machine, means for applying solvent liquid to copy sheets comprising a pair of parallel and mutually contacting rollers through which such sheets pass, a flat elongated capillary pad, a rigid tray supporting said pad, means for slidably mounting said tray and the supported capillary pad therein whereby such pad is inclined upwardly towards the underside of the uppermost roller just ahead of the bight of said pair of rollers, said pad and its supporting tray being movable in its own plane to present the uppermost longitudinal pad edge in substantially radial abutting relationship to the peripheral surface of said uppermost roller, means for

resiliently urging said tray and its supported pad in its plane of permitted movement towards said roller, stationary liquid distributor means overlying and spaced above the lower region of the uppermost side surface of said pad in said tray, a container for solvent liquid, means for delivering a regulable quantity of solvent liquid from said container to said stationary distributor means for discharge by gravity on to the lower region of said pad, and means for draining any surplus liquid at the lower end of said pad back to said container.

4. In a duplicating machine, a main framework, a machine drive shaft journalled in said framework, means for applying solvent liquid to copy sheets comprising a pair of parallel and mutually contacting rollers through which such sheets pass, a flat elongated capillary pad, a rigid tray supporting and gripping said pad, means for mounting said tray and said supported pad in a readily detachable manner in fixed guideways secured to the frame of the machine whereby said pad lies in and is movable bodily in a plane which is inclined upwardly towards the under half surface of the uppermost roller of said pair of rollers so as to present the uppermost longitudinal edge of said pad to said uppermost roller just ahead of the bight of said rollers, spring means for constantly urging said tray and said pad therein along said fixed guideways towards said roller, an apertured liquid distributing pipe secured to fixed elements of the machine frame so as to lie spaced above the uppermost side surface of and parallel with the lower longitudinal edge of said pad, a container for solvent liquid, and mechanical pumping means actuated from said machine drive shaft for delivering solvent fluid from said container to said apertured distributing pipe for distribution by gravity on to the lower end of said pad.

5. In a duplicating machine, a main framework, a machine drive shaft journalled in said framework, means for applying solvent liquid to copy sheets comprising a pair of parallel and mutually contacting rollers through which said sheets are passed, a flat elongated capillary pad, a rigid tray supporting and gripping said pad, fixed upwardly inclined guideways secured at opposite transverse sides of the said framework, means on said rigid tray for engagement within said guideways whereby said tray and the pad supported therein lies in and is movable in a plane which is inclined upwardly towards the uppermost roller of said pair of rollers, spring urged means for constantly urging said tray and said supported pad upwardly along said guideways whereby the upper longitudinal edge of said pad is pressed resiliently against the peripheral surface of said uppermost roller just ahead of the bight between the rollers, a first apertured liquid distributing pipe rigidly mounted overlying the uppermost side surface of and parallel with the lower longitudinal edge of said pad, a second apertured liquid distributing pipe surrounding and concentric with said first pipe, a container for solvent liquid, and mechanical pumping means actuated from said machine drive shaft for delivering solvent fluid from said container through said first apertured distributing pipe into said second surrounding pipe and thence on to the lower end of said pad.

6. In a duplicating machine, a main framework, a machine drive shaft journalled on said framework, means for applying solvent liquid to copy sheets comprising a pair of parallel and

7. In a duplicating machine, means for applying solvent liquid to copy sheets comprising a roller rotatable about a horizontal axis and against which said copy sheets are pressed during their delivery to the machine, a flat and elongated capillary pad disposed parallel with the axis of said roller in a plane which is inclined upwardly towards said roller and with the uppermost longitudinal edge of said pad in contact with the peripheral surface of said roller, means for distributing solvent liquid evenly along the longitudinal dimension of said pad and disposed above and in spaced relationship to the uppermost side surface of such pad at a region towards its lowermost edge and means for delivering a regulable quantity of solvent liquid to said liquid distributing means in timed relationship to the operation of the machine.

8. In a duplicating machine, means for applying solvent liquid to copy sheets comprising a roller rotatable about a horizontal axis and against which said copy sheets are pressed during their delivery to the machine, a flat and elongated capillary pad disposed parallel with the axis of said roller in a plane which is inclined upwardly towards said roller and with the uppermost longitudinal edge of said pad in contact with the peripheral surface of said roller, means for distributing solvent liquid evenly along the longitudinal dimension of said pad and disposed above and in spaced relationship to the uppermost side surface of such pad at a region towards its lowermost edge and means for delivering a regulable quantity of solvent liquid to said liquid distributing means in timed relationship to the operation of the machine.

9. A duplicating machine in accordance with claim 8 wherein said means for distributing solvent liquid evenly along the longitudinal dimension of the pad comprises a first apertured pipe rigidly mounted so as to overlie the lower edge region of said pad and a second apertured pipe surrounding said first pipe.

10. A duplicating machine in accordance with claim 9 wherein said first pipe is in fluid connection with said liquid delivering means and is provided a number of spaced apart holes and wherein said second pipe is sealed at each end and is provided with a number of spaced apart holes, such holes being relatively large in number and relatively small in size, compared with those of said first pipe.
